UNITED STATES PATENT OFFICE.

CARL H. BISSELL, OF SYRACUSE, NEW YORK, ASSIGNOR TO CROUSE-HINDS COMPANY,
OF SYRACUSE, NEW YORK, A CORPORATION OF NEW YORK.

LAMP-SHADE HOLDER.

1,345,741.

Specification of Letters Patent. Patented July 6, 1920.

Application filed July 13, 1918. Serial No. 244,778.

To all whom it may concern:

Be it known that I, CARL H. BISSELL, a citizen of the United States, and a resident of Syracuse, in the county of Onondaga and State of New York, have invented a certain new and useful Lamp-Shade Holder, of which the following is a specification.

This invention has for its object a shade holder particularly applicable for holding a shade for electric lamps and for connection to a conduit outlet box supporting the lamp socket which shade holder is particularly simple in construction and highly efficient and durable in use; and the invention 15 consists in the novel features and in the combinations and constructions hereinafter set forth and claimed.

In describing this invention, reference is had to the accompanying drawings in which 20 like characters designate corresponding parts in all the views.

Figure 1 is a side elevation of my lamp shade holder, a conduit outlet box and the contiguous portion of a lamp being also 25 shown.

Fig. 2 is a sectional view, partly in elevation taken centrally in Fig. 1, the shade being omitted.

Fig. 3 is an elevation of the detached 30 shade holder.

This lamp shade holder comprises, generally, an expansible and contractile shell or sleeve and means for contracting the sleeve including a member in the form of a spiral coil surrounding the sleeve.

The shell or sleeve is usually formed with a conoidal portion provided with a peripheral spiral groove, and the clamping member is also in the form of a conical helix and 35 lies in said groove.

1 designates the shell or sleeve which is usually formed of resilient sheet metal, it being provided with a plurality of spring tongues 2 formed by splitting or slotting the 40 sleeve lengthwise from its outer end toward its inner end or base 3.

The intermediate portion 4 of the sleeve is formed conoidal and increases in diameter toward the outer or lower end of the shell 45 and said conoidal portion is corrugated to form a peripheral spiral groove or thread 5.

The lower or outer ends of the tongues 2 are deflected inwardly at 6 and the extreme ends thereof turned outwardly forming a

bead 8 for entering the annular external 55 groove at the upper end or neck of the shade 9.

10 is the clamping member which is of wire in the form of a conical spiral coil, said member 10 encircling the conoidal portion 4 60 of the shell and lying in the groove 5.

When the member 10 is turned to move upwardly the spring tongues 2 expand so that shade 9 can be removed from engagement with the bead 8. When the member 10 is turned downwardly on the conoidal portion of the sleeve, the spring tongues 2 are contracted to cause the lower ends thereof to snugly engage the neck of the shade 9.

The unslotted base portion 3 of the shell 70 or sleeve 1 is encircled by a ring 11 which is secured thereto in any suitable manner as by rivets 12 and the ring is provided with an outwardly extending annular flange 13 by means of which the shell is attached to a 75 support as a conduit outlet box 14 in which the lamp socket 15 is located.

In operation, the spiral clamping member is placed on the sleeve from the outer end of the sleeve by contracting the sleeve as much 80 as possible and expanding the spiral coil 10 over the widest part of the conoidal portion of the sleeve, the coil 10 being slightly resili- 85 ent and expansible. The base portion of the shell is then inserted in the opening in one side of the box 14 and the flange 13 laps the outer face of the margin 16 of the wall around said opening and is secured thereto in any suitable manner as by screws.

What I claim is:

1. A lamp shade holder comprising an expansible and contractile sleeve and a member for contracting the sleeve in the form of a spiral coil encircling the sleeve and rotatable thereon and movable axially thereof during 95 the rotatable movement, substantially as and for the purpose described.

2. A lamp shade holder comprising an expansible and contractile sleeve, and a member for contracting the sleeve in the form of a spiral coil encircling the sleeve and movable axially thereon, the sleeve being formed with an external spiral groove for receiving the convolutions of said member, substantially as and for the purpose specified. 100

3. A lamp shade holder comprising a sleeve having a conoidal portion, and a member in the form of a spiral coil en-

circling the conoidal portion of the sleeve, substantially as and for the purpose set forth.

4. A lamp shade holder comprising a sleeve having a conoidal portion, and a member in the form of a conical spiral coil on the conoidal portion of the sleeve, the conoidal portion of the sleeve being formed with a spiral groove for receiving the 10 volutions of said member, substantially as and for the purpose described.

5. A lamp shade holder comprising a sleeve split longitudinally from one end toward the base of the sleeve forming a plu-

rality of spring tongues, the sleeve having a 15 conoidal portion increasing in diameter toward the free ends of the tongues, the conoidal portion being formed with a spiral groove and a clamping member in the form of a conical spiral coil encircling the 20 conoidal portion of the sleeve and lying in a spiral groove thereof, substantially as and for the purpose described.

In testimony whereof, I have hereunto signed my name, at Syracuse, in the county 25 of Onondaga, and State of New York, this 6th day of July, 1918.

CARL H. BISSELL.
